UNITED STATES PATENT OFFICE.

HERMAN E. ALTGELT, OF SOUTH BEND, INDIANA, ASSIGNOR TO OLIVER CHILLED PLOW WORKS, OF SOUTH BEND, INDIANA.

PLANTING MACHINE.

Application filed October 17, 1925. Serial No. 63,906.

This invention relates to improvements in planting machines and more particularly to improved means for locking a seed can to its support,—one object of the invention being to provide simple means to lock the seed can to its support and permit the can to be readily moved or removed from the planter for the purpose of changing the plates or for emptying or filling the can.

10 A further object is to provide a locking means for a seed can, in which the locking pin or bolt will be held in unlocked position and thus prevented from swinging freely, and in which the holding spring will be 15 gradually compressed when the pin or bolt is being moved from unlocked to locking position.

With these and other objects in view, the invention consists in certain novel features 20 of construction and combinations of parts as hereinafter set forth and pointed out in the claims.

In the accompanying drawings,—

Figure 1 is a vertical sectional view illustrating an embodiment of my invention, and 25

Figure 2 is a plan view.

In Figure 1 of the drawings, a base or support casting is indicated at 1 provided with a spout 2 as shown in Figures 1 and 30 2. The base casting 3 of a can 4 is mounted upon the support casting 1 and is provided with a tongue 5 which enters a hole 6 in an arm 7 projecting from the supporting casting 1 and in this manner the can is hinged 35 to the supporting casting.

Diametrically opposite the hinge construction above described, the support casting 1 is provided with a laterally projecting arm 8 and the base casting 3 of the can is 40 provided with a laterally projecting arm 9 which, when the parts are in normal position, overlies the arm 8. The arm 9 on the casting 3 is bifurcated and receives between its members a locking pin or bolt 10 which 45 is pivotally supported by said arm 9 through the medium of a pin 11. The arm 8 on the support casting 1 is also bifurcated for the accommodation of the locking bolt 10. The locking bolt 10 may be provided 50 at its free end with a head 12 forming a shoulder 13 against which latter, one end of a spring 14 bears. The other end of said spring bears against a plate or disk 15 which, when the parts are in locked position 55 as shown in full lines in Figure 1, bears

against the flat bottom of the arm 8. When the locking bolt is in unlocked position it will be held in vertical position as shown in dotted lines in Figure 1, by the spring 14 pressing the plate or disk 15 downwardly 60 on the flat upper portion 16 of the arm 9. The outer end portions of the members of arm 9 are curved as indicated at 17 and the outer end portions of the members of arm 8 are curved as at 18,—the curved portions 65 17—18 of the arms 8 and 9 being eccentric to the pivot mounting of the locking pin or bolt 10.

When the locking pin or bolt 10 is moved from the unlocked position shown in dotted 70 lines in Figure 1 to the locked position shown in full lines in said figure, the disk or plate 15 will ride on the curved portions 17—18 of the arms 8 and 9 and during such movement of the locking bolt, the spring 75 14 will be gradually compressed until the locked position of said bolt is reached. When the bolt is in unlocked position as shown in dotted lines in Figure 1, the spring 80 14 will be but slightly compressed but it will exert sufficient force to retain the disk or plate 15 in contact with the flat top of the arm 9 and thus hold the locking bolt in an upright position and preventing it from swinging freely and dangling from 85 the can base casting.

Having fully described my invention what I claim as new and desire to secure by Letters-Patent is:

1. The combination with a seed can and a support therefor, of a pivoted locking bolt connected with the can and cooperable with said support, and spring means operable to hold said locking bolt in unlocked position when the latter is disconnected from the support.

2. The combination with a seed can and a support therefor, of a locking bolt pivotally connected with the seed can and cooperable with the support, a spring operable to hold the locking bolt in locked or unlocked position, and means whereby said spring is compressed during the movement of the locking bolt from unlocked to locked position.

3. The combination with a seed can, a bottom casting therefor and a support casting, of a bifurcated arm on said bottom casting, a bifurcated arm on the support casting, a locking bolt pivoted in the bifurcated arm

on the bottom casting and movable between the members of the bifurcated arm on the support casting, a plate on said bolt, and a spring between said plate and the free end of the bolt, said plate being pressed by the spring against the bottom of the arm on the support casting when the bolt is in locked position and said plate being pressed against the top of the arm of the bottom casting when the bolt is in unlocked position.

4. The combination with a seed can, a bottom casting therefor and a support casting, of a bifurcated arm on the bottom casting having a flat top portion, a bifurcated arm on the support casting, a locking bolt pivoted in the bifurcated arm of the bottom casting and movable between the members of the arm on the support casting, said

arms having curved portions eccentric to the pivot mounting of the locking bolt, a plate on said locking bolt, and a spring between said plate and the free end portion of the bolt, said spring operable to hold the plate against the bottom of the arm on the support casting when the bolt is in locked position and to hold said plate against the flat top of the arm on the base casting when the bolt is in unlocked position, said plate being adapted to ride over the curved portions of said arms when the bolt is being moved from its unlocked to its locked position, whereby compression of the spring will be effected automatically.

In testimony whereof, I have signed this specification.

HERMAN E. ALTGELT.
